UNITED STATES PATENT OFFICE

102,023

DESIGN FOR A CARRYING HANDLE

George A. Adams, Rochester, N. Y., assignor, by
mesne assignments, to Eastman Kodak Com-
pany, Jersey City, N. J., a corporation of New
Jersey

Application April 7, 1936, Serial No. 61,989

Term of patent 14 years

To all whom it may concern:

Be it known that I, George A. Adams, a citizen
of the United States, residing at Rochester, in
the county of Monroe and State of New York,
have invented a new, original, and ornamental
Design for Carrying Handles, of which the fol-
lowing is a specification, reference being had to
the accompanying drawing, forming a part
thereof.

In the drawing:

Fig. 1 is a side elevation of a carrying handle
in the position in which it would appear when at-
tached to a camera or other article of similar pro-
portions showing my new design.

Fig. 2 is a perspective view showing the handle
on a somewhat enlarged scale from the showing
of Fig. 1.

Fig. 3 is a fragmentary plan view of the central
portion of the handle on a large scale for the pur-
pose of more clearly bringing out the details of
the design.

I claim:

The ornamental design for a carrying handle
as shown and described.

GEORGE A. ADAMS.
